UNITED STATES PATENT OFFICE.

SAMUEL WEINSCHENK, OF NEW YORK, N. Y.

UMBRELLA RACK AND SMOKING STAND.

Application filed March 12, 1925. Serial No. 15,000.

To all whom it may concern:

Be it known that I, SAMUEL WEINSCHENK, a citizen of the United States, and a resident of the city of New York, Richmond Hill, 5 borough of Queens, in the county of Queens and State of New York, have invented a new and Improved Umbrella Rack and Smoking Stand, of which the following is a full, clear, and exact description.

10 This invention relates to furniture and particularly to a combined umbrella rack and smoking stand capable of various adjustments, the object being to provide a construction which may be easily converted 15 so as to be used in different capacities.

Another object of the invention is to provide a stand which may be adjusted to act as a table, a smoking stand or umbrella rack.

20 A further object, more specifically, is to provide an article of furniture having a number of hinged members which may be quickly swung into different positions without injuring any of the parts and without 25 presenting unsightly structures while adapting the device for a large number of different uses.

In the accompanying drawings—

Figure 1 is a perspective view of the device in an unfolded or open condition.

Figure 2 is a vertical sectional view through the structure shown in Figure 1, the same being on a slightly enlarged scale.

Figure 3 is a view of the structure shown 35 in Figure 1 with a slightly modified structure associated therewith for converting the stand into a card table.

Figure 4 is a perspective view similar to Figure 1 but showing the parts adjusted 40 whereby the device presents a smoking stand.

Referring to the accompanying drawings by numerals, 1 indicates a plurality of legs which are braced at a suitable point by a 45 platform 2 while at the top the legs are connected together by the side walls 3 and 4 and by a rear wall 5. Instead of a front wall there are provided bars 6 and 7 between which the bore 8 is fitted, said bore 50 being held in position by any suitable means, as for instance, hinges 9. Connected to the bottom portions of the side walls 3 and 4 are bottom members 10 and 11 which are hingedly connected to the side 55 members by suitable hinges 12 and 13 and which are limited in their downward move-

ment by suitable supporting bars 14. Pivots connected to the side walls 3 and 4 by suitable hinges 15 and 16 are top pieces 17 and 18. These top pieces may be made 60 solid throughout or in some other way but preferably the top piece 18 is made solid throughout as shown particularly in Figure 4 while the piece 17 is provided with a number of apertures 19 through which umbrellas are adapted to be passed when the top piece 17 is resting on top of the side walls as shown in dotted lines in Figure 2. When the top piece 17 is in use, the bottom members 10 and 11 are hinged to a vertical position 65 as shown in dotted lines in Figure 2 whereby the umbrellas may be passed through the various apertures 19 and the lower ends caused to rest on the platform 2. If desired, a pan could be provided on the platform 2 to take care of the drainage water. When the top piece 17 is in use, the door 8 is closed and the top piece 18 is 70 swung to one side out of the way but still in position to be used instantly whenever 75 desired.

When it is desired to use the device for a smoking stand, the parts are re-arranged as shown in Figure 4, namely, the top piece 17 is swung to a position along side of two 80 of the legs 1 while the top piece 18 is moved over to form a top plate. The bottom members 10 and 11 are left in their lower position so that tobacco, matches and the like 85 may be placed in the chamber provided by the various side walls and bottom members 90 10 and 11.

In case it should be desired to use the device for a card table or table of some kind where more space is necessary, the 95 modified structure shown in Figure 3 may be used. In this structure it will be noted that cleats 20 and 21 are provided so as to receive an auxiliary plate 22 acting as a top plate while the top pieces 17 and 18 are 100 connected to the side walls 3 and 4 by ordinary hinges 23 and 24 instead of the special hinges 15 and 16, which special hinges are provided with one long leaf and one short leaf. In order to properly support 105 the top pieces 17 and 18 in a horizontal position, suitable bracing rods 25 and 26 are provided, one end fitting into notches 27 and 28 while the opposite ends are bent so as to fit properly into straps 29 and 30. 110 The strap 29 is positioned so as to avoid the various apertures 19 while the strap 30 is

preferably positioned centrally of the top piece 18.

In the form shown in Figures 1, 2 and 4, all the parts are connected together in some manner and remain as part of the stand continually though adjusted to be in a useful position or in a position stored out of the way. In Figure 3, however, there are some extra parts, namely, the plate 22 and braces 25 and 26 which may be left in place or removed as desired.

What I claim is:—

1. A stand, comprising a plurality of supporting legs, means forming an open top chamber at the top of the legs, and a pair of top members hinged to be alternately swung over to form a top piece covering said chamber, one of said top pieces being solid to form a solid top so that the device 20 may act as a telephone or smoking stand and the other formed with comparatively large apertures whereby the device may act as an umbrella stand.

2. A stand, comprising a plurality of supporting legs, an apertured plate hingedly connected with certain of said legs at the top, a solid plate hingedly connected with certain of said legs at the top, each of said plates when in one position acting as a covering or top plate whereby the device 30 may act as a smoking stand when the solid plate is being used and as an umbrella stand when the apertured plate is being used.

3. A stand, comprising a plurality of supporting legs, a pair of side plates connected to said legs at the upper end, an end plate connected to said legs at the upper end, a door positioned diametrically opposite said end plate, a pair of bottom plates 40 hingedly connected with said side plates and adapted to be swung to a vertical position when not in use, means presenting a solid top for said stand, said means being hingedly mounted so that when in use it 45 will present a solid top and when not in use may be swung to one side and an apertured plate for said stand adapted to be used when the stand is used for an umbrella rack, said apertured plate being 50 hingedly mounted so that when in use it acts as a top plate and when not in use is

adapted to be swung to one side, said means and said apertured plate being used as a top plate at different times, said hinged bottom plates being moved to a vertical position when said apertured plate is in use.

4. A stand, comprising a plurality of supporting legs, means forming a boxing at the top, a top plate for said boxing acting as a cover therefor, said top plate having a plurality of apertures through which umbrellas may be passed so that the device will act as an umbrella stand, and hinge members for hingedly connecting said top plate in position, said hinge members being 60 provided with a long leaf whereby the pintle of the hinge members will be spaced from said boxing and permit the top piece to be swung downwardly and flatwise against the sides of the boxing when not 70 in use.

5. A combined umbrella rack and smoking stand, comprising a plurality of supporting legs, means for bracing the legs near the lower end, means forming a chamber at the upper end which is open at the top and one side, a door hinged to close said open side, and a pair of top plates hinged to close at different times said open top, one of said top plates being formed 80 with apertures through which umbrellas may be passed.

6. A combined umbrella rack and smoking stand, comprising a plurality of supporting legs, means forming a chamber for the top of said legs, said chamber being open at the top and one side, the bottom of said chamber being formed by a pair of hinged members capable of being moved from a horizontal to a vertical position, a 85 hinged door for closing the open side of said chamber, and a pair of hinged covering members for closing the top of said chamber, one of said covering members having a plurality of apertures whereby umbrellas 90 may be passed therethrough, the hinged bottom members being moved to a vertical position when the apertured top member is used in order to permit the umbrellas to extend downwardly beyond this chamber.

SAMUEL WEINSCHENK.
